UNITED STATES PATENT OFFICE

2,515,247

KNIFE SHARPENER

Frank S. McCabe, Kenilworth, Ill.

Application February 5, 1947, Serial No. 726,539

1 Claim. (Cl. 51—116)

1

The present invention relates generally to utility devices, and more particularly to a knife sharpener.

An object of the present invention is to provide a novel knife sharpener which is adapted to accurately, efficiently, and safely sharpen knives.

Another object is to provide a novel knife sharpener in which the knife edge is self directed into proper position in respect to blade sharpening members.

Another object is to provide a novel knife sharpener incorporating a slotted shield through which the knife blade extends for contact with blade sharpening wheels, which, in addition to forming a guide for sharpening purposes, reduces to a minimum the possibility of the user being cut by the blade during the sharpening action.

Another object is to provide a novel knife sharpener incorporating removable and reversible knife sharpening wheels.

Another object is to provide a novel knife sharpener which is mounted on a frame adapted to be disposed on a post bracket for swinging out of the way when not in use.

Other objects are to provide a novel knife sharpener which is sturdy in construction, in which the blade sharpening parts are replaceable, which may be readily employed by a user with maximum efficiency after minimum instruction, which is relatively inexpensive, and which may be readily fabricated.

The foregoing and other objects and advantages are apparent from the following description taken in connection with the accompanying drawing, in which:

Fig. 1 is a side elevational view of a knife sharpener constructed in accordance with the teachings of the present invention, mounted on a bracket secured to a wall for swinging out of the way when not in use;

Fig. 2 is a fragmentary plan view of the knife sharpener;

Fig. 3 is an elevational view similar to Fig. 1, showing the other side of the knife sharpener;

Fig. 4 is an end elevational view thereof, a part of the handle being broken away for conservation of space;

Fig. 5 is a vertical transverse cross-sectional view on the line 5—5 of Fig. 1, a portion of the handle being broken away for conservation of space; and

Fig. 6 is an enlarged fragmentary cross-sectional view of the two abrasive wheels.

Referring to the drawing more particularly by

2

reference numerals, 10 indicates generally a knife sharpener incorporating the concepts of the present invention. The knife sharpener 10 includes a body 12, preferably of metal, formed as a wall 14 from which extends a horizontal flange 16 and a vertical flange 18 which merge in a substantially arcuate corner 20, as is clear from Fig. 3. The wall 14 includes reinforcing bosses 22 and an aperture 24 which receives a bushing 26 peened over and secured to the edges of the aperture 24, as is clear from Fig. 5.

A shaft 28 is rotatably supported in the bushing 26 and includes a reduced portion 30 having a threaded extremity 32. Two blade sharpening discs 34 are disposed in contiguous relation and are mounted on the reduced portion 30 of the shaft 28 for rotation therewith, as is shown in Fig. 5, a large washer or disc 36 being disposed against the outer surface of each, one washer 36 bearing against the shoulder of the shaft 28 formed at the juncture of the reduced portion 30 and the main portion thereof, and the other washer 36 being securely engaged by a nut 38 threaded onto the extremity 32. The discs 34 are shown as of abrasive material, but metals or other materials may be used. The preferred cross section of the abrasive discs 34 is shown in Figs. 5 and 6, the periphery of each being rounded to provide an annular V-groove 35 when in contiguous relation. A crank arm 40 is secured to the end of the shaft 28 for rotation therewith and has a knob 42 connected to its free end, preferably being rotatably mounted on a stud 44 to insure ready rotation of the discs 34.

As is clearly shown in Figs. 2 and 4, a continuous slot 46 is formed in the flanges 16 and 18. The slot 46 is formed at an angle to the vertical in the flange 18, being disposed at an angle of about 7° to the vertical for a major portion of the length in the flange 18, changing to an angle of about 14° for the remainder of its length in the flange 18 and continuing at the same angle of substantially 14° in the horizontal flange 16. It is clear from the drawing that the slot 46 crosses the common plane of the abrasive discs 34. In a preferred form, a slot 46 of a width of between seven and eight one-hundredths of an inch has been used.

The body 12 is secured by rivets 50 to the flange 52 of a sleeve 54, which is shown removably disposed about a post 56 mounted in upright position on the horizontal flange 58 of a bracket 60, the vertical flange 62 of which is shown secured to a wall 64 by suitable screws 66. The bracket 60 includes a second horizontal flange 68 to

steady the post 56. The flange 58 includes peripheral notches 70 which receive selectively a heel 72 of the flange 52 for disposing the knife sharpener 10 at right angles to the wall 64, or alongside thereof, as desired.

Operation

It is manifest from the foregoing that rotation of the shaft 28 by the knob 42 effects rotation of the abrasive discs 34 since both the abrasive discs 34 and the crank arm 48 are secured to the shaft 28 for rotation therewith. With the abrasive discs 34 rotating away from an individual standing in front of the knife sharpener 10 (clockwise in Fig. 1), a knife blade placed in the slot 46 will have the edge thereof contacted by both abrasive discs 34, so that sharpening action is simultaneously applied to both sides of the blade to effect a keen edge. The location of the slot 46 in respect to the abrasive discs 34 is such that a user need but insert the blade of a knife in the slot 46 and move it longitudinally of the slot while rotating the abrasive discs 34.

It is clear that the flanges 16 and 18 form a shield to prevent one using the knife sharpener 10 from being burned by the fast moving abrasive discs 34 and from being cut by the keen edge of a knife being sharpened, occasioned by injudicious disposition of the hands while sharpening the knife or from an accidental slip during the sharpening. In the present device, the hands are shielded from both abrasive discs 34 and the knife edge.

It is also clear from the foregoing that the present knife sharpener 10 eliminates the difficulty of getting a proper edge on a knife which is inherent in the usual types of knife sharpeners now available to the public. Since the knife edge is guided into proper relationship with the abrasive discs 34 by the slot 46, the obtaining of a keen edge becomes routine with the present novel device.

It is to be understood that a second slot may be formed in the flanges 16 and 18 crossing the first slot 46 at an angle to form an X. The second slot will be formed in identical respects to the flanges 16 and 18 and other elements of the knife sharpener 10 as the slot 46 is formed, except its course will be from right to left (Fig. 4) instead of from left to right.

It is apparent that there has been provided a

knife sharpening device which fulfills all of the objects and advantages sought therefor.

It is to be understood that the foregoing description and the accompanying drawing have been given by way of illustration and example. It is also to be understood that changes in form of the several parts, substitution of equivalent elements, and rearrangement of parts, which will be readily apparent to one skilled in the art, are contemplated as within the scope of the present invention, which is limited only by the claim which follows.

What is claimed is:

A knife sharpener comprising a housing having an elongated plate portion provided with merging connected top and front end flanges extending substantially right angularly from the inner side of said portion and terminating in free edges in a plane substantially parallel to the plane of the plate portion, means provided on the rear end of said portion for mounting the housing on a supporting member, a bearing extending from the outer side of the plate portion substantially equidistant from said flanges, a shaft journaled in the bearing, abrasive wheel means removably mounted on the inner end of the shaft and provided with a peripheral groove adjacent to and partly surrounded by said flanges, and a handle for rotating the shaft fixed on the outer end of the shaft, the flanges being slotted to admit a knife edge to the groove of the abrasive wheel means and said wheel means being removable for replacement from the open inner side of the housing.
